L. D. GIBSON

LOCK

Filed Oct. 31, 1924

Inventor
LEE D. GIBSON

Ch. Parker
Attorney

UNITED STATES PATENT OFFICE.

LEE D. GIBSON, OF DALLAS, TEXAS.

LOCK.

Application filed October 31, 1924. Serial No. 747,108.

To all whom it may concern:

Be it known that I, LEE D. GIBSON, a citizen of the United States, residing at Dallas, in the county of Dallas and State 5 of Texas, have invented certain new and useful Improvements in Locks, of which the following is a specification.

This invention relates to locks, and is an improvement over the construction shown in 10 my copending application, Serial No. 725,840, filed July 12, 1924.

An object of the invention is the provision of a padlock having a pair of plungers adapted to engage the hasp of the lock.

15 A further object of the invention is the provision of a lock construction in which the lock casing is provided with a number of compartments, the plungers arranged in one compartment and the key adapted to be 20 received in another compartment whereby opening of the lock by jimmying the key is prevented.

A further object of the invention is the 25 provision of a lock in which the locking plungers are actuated by a pair of pivoted dogs and are retained in locked position by a locking member, the dogs and the locking member being controlled by a single key.

In the accompanying drawings, I have 30 shown one embodiment of the invention. In this showing:

Figure 1 is a front elevation of the lock, parts being shown in section,

Figure 2 is a horizontal sectional view on 35 line 2—2 of Figure 1,

Figure 3 is a similar view on line 3—3 of Figure 1.

Figure 4 is a similar view on line 4—4 of Figure 1,

40 Figure 5 is a vertical sectional view on line 5—5 of Figure 1,

Figure 6 is a detail view of portions of the lock disassembled, and,

45 Figure 7 is a perspective view of the pivoted dogs.

Referring to the drawings, the reference 50 numeral 1 designates generally a lock casing which may be of any desired form and which is shown rectangular. The casing is formed of a block of metal which is cut out to form the various compartments of the lock and to provide partition walls separating the compartments. As shown, the casing is provided with a wall 2 parallel to 55 one side, and spaced a slight distance therefrom, forming a chamber 3 for the recep-

tion of one arm of the hasp. It is further provided with a transverse partition 4, forming a compartment 5 for the reception of the key and the key mechanism. Above 60 the partition 4, there is provided a compartment 6, which is separated from an upper compartment by means of a transverse wall 7. The compartment 5 is spaced from the hasp chamber by means of a vertical wall 8 extending from the bottom of the lock casing to the partition wall 4 and a casing 9 is arranged within this space. After the various parts of the lock have been assembled in the casing, a plate 10 is arranged 70 over the open face of the casing and immovably secured thereto in any suitable manner, as by welding or the like.

The lock is adapted to receive a hasp 10 which is formed U-shaped in the usual manner and one arm 12 thereof is elongated and extends into the chamber 3 to a point adjacent the bottom of the lock casing. The other arm 13 is shorter and is adapted to 75 barely enter the top of the lock casing when in locked position. The long arm 12 is provided with a reduced lower end 14, and a coil spring 15 is arranged around this reduced portion in the bottom of the chamber 3 and is adapted to project the hasp 80 when the lock is released. As shown, a knob 16 may be formed in the bottom of the chamber 3 and receive the end of the spring to guide it. In Figure 1 it will be seen that the casing 1 is extended up into the curve 85 of the hasp 11 at 1^a and leaving an opening 2^a for a staple or the like to fasten the lock to the article to be secured. The purpose 90 of this extension is to prevent the prying of the lock by inserting a pointed instrument between the hasp and the casing. The arms of the hasp are provided with substantially V-shaped notches or recesses 17 in alignment with each other and these recesses are adapted to receive the 95 ends of locking plungers 18, which retain the lock in closed position. As shown, the plungers are arranged in a compartment formed between the top of the lock casing and the partition wall 7. A coil spring 19 is arranged between the plungers and normally forces them outwardly.

The plungers are adapted to be actuated by means of a pair of pivoted dogs 20 which are arranged in the compartment 6 and are pivotally mounted on pins 21 which are received in a transverse rib 22. The upper 100

ends of these pins extend through an elongated slot in the wall 7 and are received in notches 23 formed in the lower face of the locking plungers. These dogs are adapted 5 to be actuated by a cam 24 arranged on the end of a rod 25, which extends through the partition 4. The rod 25 is carried by a cylinder 26, the lower end of which is provided with an enlargement 27 abutting the inner 10 side of the bottom of the lock casing. The lock casing is provided with an opening in alignment with the cylinder, and a tubular spacing member 28 is secured to the cylinder and extends through this opening. Externally of the casing, the tubular spacing member is provided with an enlargement 29 similar to the enlargement 27. The cylinder is provided with a groove 30 which, as shown, may be spirally arranged and is 15 adapted to receive a key 31 which is twisted to fit in this groove. The partition 8, which forms one of the walls of the casing 9, is provided with spaced cut out portions or notches 32. A locking plunger 33 is arranged within this casing and is normally 20 forced outwardly by means of a spring 34. This plunger is provided with a pair of grooves 35 in the face adjacent the wall 8 and these grooves extend across the face 25 of the plunger at an angle (see Figure 5). The key 31 is provided with ribs or extensions 36 which are adapted to pass through the notches 32 and enter the grooves 35. The locking plunger is provided with an 30 extension 37 which is reduced in cross section and extends through the compartment 6. The partition 7 is provided with an 35 opening through which the end of the locking plunger 33 is adapted to pass and the locking plunger 18 is provided with a slot or notch 38 in alignment therewith when the plunger is in operative position to receive the end of the plunger 33. Adjacent the 40 end of the plunger, there is provided an enlargement forming a shoulder 39, which is adapted to contact with the lower face of the partition 7.

In operation, the key is inserted in the cylinder 26 from the bottom of the lock casing and rides in the groove 30. The fingers 36 project from the cylinder. The cylinder is then rotated by turning the head of the key and the lower finger 36 first enters the lower groove 35 through the slot 32. As 45 the key is rotated, this moves the plunger downwardly. After a slight further rotation, the upper finger enters the upper groove and the continued rotation of the key draws the member 33 inwardly, releasing its upper end from the notch 38. At 50 the same time, the dogs 20 are swung on their pivots by the cam 24, the lower end of the dogs being forced outwardly and the upper ends moving toward each other. 55 This inward movement of the dogs with-

draws the locking plungers 18 from the recesses 17 in the hasp and places the spring 19 under tension. The spring 15 then projects the hasp and when the short arm 13 is projected, it is arranged above the top of the casing and the lock is unlocked. When the key is turned through a complete half revolution and withdrawn from the cylinder, the parts are ready to assume an operative position and as soon as the hasp is 70 forced home, the spring 19 returns the locking plungers 18 to their operative position. At the same time, the locking member 33 is forced upwardly by the spring 34 and when the plungers 18 assume their operative position, the upper end of the member 33 enters the notch 38.

It is to be understood that the form of my invention herewith shown and described is to be taken as a preferred example of the 85 same, and that various changes in the shape, size, and arrangement of parts may be resorted to without departing from the spirit of the invention or the scope of the subjoined claims.

I claim:

1. A lock as described and shown comprising a casing, a major locking plunger and minor locking plungers therein, a spiral key with fingers engageable in slots in said major locking plunger for moving said major locking plunger downward from engagement with one of said minor locking plungers; and means for releasing said minor locking plungers from engagement with the hasp 100 when the key is rotated to move the major plunger.

2. A lock as described and shown, comprising a casing, a slotted cylinder with a spiral key with fingers, the latter engageable in obliquely disposed slots in a major plunger to pull it downward on rotation of the key; minor plungers engageable with said hasp, dogs for moving the minor plungers from said engagement when the major plunger is moved downward, and means for projecting the minor plungers to locked position.

3. A lock of the character described comprising a casing, a hasp secured therein, minor locking plungers for engagement with said hasp, a vertically movable major locking plunger adapted to engage one of said minor locking plungers for retaining the latter in engagement with the hasp, a vertically extending key cylinder rotatably mounted within said casing, means operatively connecting the upper end of said cylinder with said minor locking plungers whereby the latter may be moved out of engagement with the hasps upon rotation of said cylinder, and the key for said cylinder adapted to engage said major locking plunger for withdrawing the latter from engagement with one of said minor locking plungers.

4. A lock of the character described comprising a casing, a hasp secured within said casing, partitions formed with said casing for dividing the same into a plurality of compartments, minor locking plungers mounted within one of said compartments, a major locking plunger mounted within another compartment, the upper end of said major locking plunger adapted to project at 10 times within the minor locking plungers compartment for engagement with one of said minor locking plungers, dogs pivotally supported in another compartment of said casing and adapted to extend within the minor locking plungers compartment for engagement with said plungers, a key cylinder arranged in another compartment, a cam carried by said cylinder and arranged in said dogs compartment for engagement therewith, and a key for said cylinder adapted to extend at times within said major locking plunger compartment for engagement with said major locking plunger.

In testimony whereof, I affix my signature.

LEE D. GIBSON.
